(57) **CLAIM**

The ornamental design for a container with a handle, as shown and described.

DESCRIPTION

FIG. 1 is a perspective view of a container with a handle showing my new design in a closed lid position;

FIG. 2 is a left side elevational view thereof;

FIG. 3 is right side elevational view thereof;

FIG. 4 is a front elevational view thereof;

FIG. 5 is a rear elevational view thereof;

FIG. 6 is a top plan view thereof;

FIG. 7 is a bottom plan view thereof; and,

FIG. 8 is a left side elevational view thereof in an open-lid position.

The broken lines shown are included for the purpose of illustrating environment and form no part of the claimed design.
